UNITED STATES PATENT OFFICE.

ROBERT V. BINGAY, OF PITTSBURGH, PENNSYLVANIA, ASSIGNOR TO PITTSBURGH
TRANSFORMER COMPANY, A CORPORATION OF PENNSYLVANIA.

METHOD FOR FORMING TRANSFORMER STRUCTURES.

Original application filed June 2, 1920, Serial No. 386,115. Divided and this application filed March 11, 1922. Serial No. 542,120.

To all whom it may concern:

Be it known that I, ROBERT V. BINGAY, a citizen of the United States, residing at Pittsburgh, in the county of Allegheny and State of Pennsylvania, have invented certain new and useful Improvements in Methods for Forming Transformer Structures, of which the following is a specification.

This application is a division of my application Serial Number 386,115, filed June 2, 1920. The invention relates to a method of making tanks of sheet steel for containing electrical transformers or other devices.

The invention will be described with reference to the accompanying drawings in which—

Fig. 1 illustrates the tank in vertical sectional view.

Figs. 2 to 12 inclusive illustrate successive steps in the formation of the tank, and

Fig. 13 illustrates the tank.

The tank K is preferably of sheet metal and preferably circular, oval or rounded in section and the sides 22 are corrugated to a depth dependent upon the size of the tank and the relative cooling surface required. Hitherto the depth of these side corrugations has been limited by considerations of strength and the difficulty and expense of producing deep corrugations. The shallower corrugations give a correspondingly restricted cooling surface and often it has been necessary to resort to extra cooling pipes or circulating means where the available air cooling of the tank itself would be sufficient if properly provided for. In the tank of this invention corrugations of the tank body may be of any desired depth and strength required by practice and at the same time these corrugations are formed from sheet metal plates in a simple and inexpensive manner and the resultant structure is strong and self-sustaining and when assembled with the top and bottom portions provides a rigid, durable container.

In building up the tank sides or body 22 a rectangular sheet 23 (Fig. 2) is chosen or cut from the standard sheet steel sizes in stock and the top and bottom edges of the sheet are notched as at 24 leaving straight intervals 25 between the notches, and in the specific example shown leaving half intervals 25' at each end. The notched sheet 23 is then bent into a series of parallel corruga-

tions (Figs. 3 and 4) and preferably the bends are made by a pivoted bender 26 swinging around a former 27 and pressing or wrapping the sheet around the former. This method of bending the corrugations in succession gives a predetermined identical diameter to each bend and avoids any overstressing of the metal and any irregular or warped effects. The bends 28, 29 at the ends of the corrugations are separated by intermediate substantially flat portions 30 and 65 the inner bends 28 are made between the notches 24 while the outer bends 29 are centered at the peaks 31 of the notches the ends of corrugated sections having the form shown in Figs. 3 and 4 with the edges of bends 28 70 at right angles to the sheet and the edges of bends 29 inclined. The corners 32 of the notches form a line near the inner bends 28.

The next step in the formation of the tank body is illustrated in Figs. 5 and 6 and comprises bending the corrugated section as a whole into a circular arc corresponding in diameter to the diameter of the tank being built. This is accomplished by pressing the inner bends 28 toward each other to slightly 80 narrow the spaces between them and correspondingly spreading apart the outer bends to increase their spacing, a template being used to gage the spacing of the bends. When a number of sections have been formed and 85 curved as shown in Figs. 5 and 6 these sections are assembled side by side in semicircular cradles 33 corresponding to the outer diameter of the tank and the assembled sections are welded together along their meeting edges which are on the inside of the tank, and in this way a circular section is built up in the form for instance of a semi-circle and corresponding to half of the tank body. The other half of the tank body is 90 similarly built up and the two halves are assembled together on circular heads or templates 35 (Fig. 10) corresponding to the inner diameter of the tank and are bound thereon by outer hoops 36. The two sections 100 are then welded together along their meeting edges at the inside of the tank.

The tank body so formed has its corrugations open at the top and bottom and the next step in the process is the closing 105 of these corrugations in such manner as to form a rigid arched structure in which the corrugations mutually support each other

through solid connecting rings at each end of the tank. The closing of the ends of the corrugations is illustrated in Figs. 7, 8, and 9 and comprises a flattening or turning 5 over of the ends of the inner corrugations 28 as indicated at 39. The end edges of these corrugations are thus flattened out into substantially straight lines as indicated at 38 and the ends of the corrugations are spread 10 so as to be brought toward and finally into contact with each other as indicated at 40 and 41. The edges of the intermediate portion 30 and the outer bends 29 are also hammered over and brought into contact along 15 line 42 and welded securely together along this line. The hammering outward of the ends of the corrugations 28 forms the inclined flattened surfaces 39 and brings the extreme ends of these surfaces substantially 20 into the line of the corners 32 of the notches 24, forming a continuous annular ridge around the end of the tank from which the corrugations incline in opposite directions.

This gives a strong arched construction 25 terminating in a solid continuous apex or peak; the end of each corrugation is arched with a central heavily welded seam, and all these arches of the corrugations converge to the top ring so that these corrugations are 30 not only strong in themselves but reinforce and mutually sustain each other through their common connection. All vertical sections through this structure show a characteristic arched form and all horizontal sections also show continuous corrugations with 35 arched connecting bends. With a tank constructed according to the method of this invention it is possible to use a very light gage of sheet steel and all sizes of tanks may be 40 made from stock only about one sixteenth of an inch thick. It is only necessary to carry a very few sizes of steel sheets in stock and from these sizes the desired sections may be 45 readily cut, the number of sections in the tank being easily varied so that a given size of sheet will serve for various sizes of tanks. Each sheet is easily notched to desired contours according to the job in hand and may be 50 notched in part and left plain in part to provide any desired shape for the tank and the sheets before corrugating may be punched out with holes of a shape which will be circular in the finally bent form. The forming of the corrugation bends around a 55 mandrel bends the metal and does not draw or warp or weaken it or leave it with internal stresses. The final closing of the corrugations and welding is done with the tank sections bound together and braced against 60 warping by the inner heads 35 and the outer bands 36.

The two ends of the tank body are substantially identical and comprise a corrugated cylinder with the corrugations inclined 65 and arched at each end and rigidly welded to

a continuous annular end portion at each end. This tank body is very strong, irrespective of its connection with the bottom and cover pieces. At each end it provides 70 an annular beveled surface formed by the ring of inclined flattened surfaces 39 and this beveled surface serves for the attachment of the bottom and top pieces in a simple and very rigid manner. When the bottom and top pieces are in place, as herein- 75 after described, this strong tubular portion reinforces the end portions in such manner that each part is trussed against the other to receive the strains put upon the tank.

The bottom M of the tank is formed by a 80 circular plate, preferably of rolled steel, with its edge flanged upwardly at an angle (Fig. 11) and this edge flange 45 of the bottom M is nearly at right angles to the beveled surfaces 39 and is just fitted to an 85 intermediate portion of these surfaces. With the bottom piece M assembled and clamped in place a heavy weld 46 is made in the corner between the surfaces 39 and the flange 45 so that the bottom surface of the tank 90 is below the surface of this weld which will therefore be held spaced from the base B of the transformer in finally assembled position. This flanging of the bottom plate M gives this plate an arched construction and 95 protects it against warping due to the heat of the welding operation and due to any strains on it in service, and this arching at the bottom also holds the welded seam away 100 from contact with the base or other surfaces so that this seam does not collect moisture and become rusty or weaken or wear in use. This construction permits the bottom plate 105 and the top ring, or either, to be made either thicker or thinner than the metal in the tank body, or of the same thickness as may be 110 most advantageous.

The top of the tank body has welded to it the steel or iron angle ring 50 formed by rolling an angle into circular form with 115 its flange 51 inclined at substantially the angle of the tank cover C and the ends of the circle welded together. This ring 50 is sized to fit into the top of the tank and engage an intermediate portion of the beveled surfaces 39 at the top and is fastened in place by heavy welding 52 all around in the annular corner between the surfaces 39 and ring 50. This ring forms additional reinforcement of the tank body and provides a 120 strong and simple connection for the tank cover C.

In the combination of this invention the method of forming the tank and the tank body in its trussed or arched structure permit the use of the sheet steel stock and this body is furthermore not required to sustain the weight of the transformer parts. The corrugations of the tank body may be made 125 of any depth to give the cooling surface 130

required. These corrugations overhang at the sides and are formed with well rounded bends 29 to give a large passage for the circulation of the oil along the most exposed surfaces and in their entire area provide an extended cross section acting like large pipes for the circulation of the oil. This system in effect makes pipes or conduits P of the corrugations which have a great proportion of their surface exposed to the air and separate the inner heated currents of oil from the outer cooled currents and an inner baffle cylinder 60 or guide vanes may be provided just within the bends 29. The columns of cooled oil in the corrugations are relatively heavy and pass down rapidly through the corrugations drawing in heated currents of oil at the top 61 and at the bottom 62 replacing the oil rising through the transformer coils.

By the method of this invention the relative area of the outer cooling flutes and the inner passages through and around the coils and core may be made in most effective proportion and this circulatory system provides definite areas of heating and cooling, avoids interference between the rising and descending currents, and in effect gives a forced circulation which by the outer rapid passing of the oil down through the corrugations distributes the heated oil over a larger area of the transformer sides and instead of accumulating as heretofore within a relatively small area at the top with slow and sluggish progress down the sides the oil is rapidly circulated downward through the pipes formed by the corrugations. The temperature gradient at the sides therefore is much less abrupt and the cooling taking place over a much larger area is much more efficient.

The tank of this invention also provides unobstructed paths for the cooling air rising around the sides and in between the corrugations. These corrugations overhang even at their lower ends so that the cooling currents of air have access at the very bottom. They also meet with warm surfaces at a relatively short distance from the bottom and their absorption of heat is distributed over a large proportion of their length of path. All of these conditions make for a thorough and efficient transfer of heat from the oil within the tank to the air outside so that the tank of this invention will efficiently cool a transformer under conditions where it has heretofore been necessary to use extra radiators or cooling coils or pump circulation.

The method and structure of this invention therefore combine an inexpensive process of manufacture with efficiency and durability in service. This invention is adaptable not only to standard lines and types of transformers to be made up in quantity

but also may be readily varied to meet the conditions of particular installations. The number of sections 23 in a given transformer body is a matter of the most economical use of the stock in hand after the desired depth of the corrugations and the total area of the body is determined. With transformers of excessively large size or where great strength is required an increase in the gage of metal in the body may make it economical to make only a single corrugation in each section 23. In such case the bend of this corrugation is directed outward and the inner meeting edges of adjacent sections are also flanged over and turned outward and welded together along the inside between these flanges as indicated at 66 (Figs. 5^a and 6^a).

While this invention has been illustrated in connection with a specific embodiment of transformer and tank it is not confined thereto but is intended to cover such modifications thereof as fall within the scope of the appended claims. It will also be understood that the parts may, if desired, be brazed instead of welded.

I claim:

1. The method of forming a tank body from a plurality of sheets comprising notching said sheets, corrugating and bending said sheets into desired shape to form the tank body with inner and outer channels between the corrugations, and bending the ends of the inner channels outward and closing the ends of the outer channels by bending them over in arched form and welding along the meeting edges, said corrugated sheets being fastened together by welding to form the tank body.

2. The method of forming a tank body from a plurality of steel sheets comprising corrugating and bending said sheets into desired shape to form the tank body, bending outward the inner portions of the ends of the corrugations to bring them together in the form of a ridge at the end of the tank, and closing the ends of the corrugations by welding, said corrugated sheets being fastened together by welding to form the tank body.

3. The method of forming a tank body comprising welding together corrugated steel sheets to form a tubular portion, bending over the ends of said corrugations so that they meet in arched form edge to edge, closing the ends of said corrugations by welding, and welding end portions to the ends of said tubular portion at the inner circumference thereof.

4. The method of forming a tank body comprising welding together corrugated steel sheets, bending the ends of the inner corrugations into a continuous circular edge, closing the ends of the corrugations by welding, and welding the edges of an end

member to the said continuous circular edge.

5. The method of forming a tank which consists in cutting a series of rectangular sheets each of which has an end cut with a series of notches and straight portions, forming in each sheet a series of parallel bends coinciding with the apexes of said notches and the middle of said straight portions, assembling said sheets by fastening the edges 10 of adjacent sheets together to form a tubular structure, bending back the inner upper ends of the corrugations to form an inclined circumferential surface, closing the outer open ends of the corrugations, fitting 15 a circular end portion against the inclined circumferential surface, and welding a filler of welding material in the angle between the edge of the end portion and the surface of the inclined portion.

20 6. The method of forming a tank of sheet metal comprising the steps of corrugating and bending the sheet metal to form a tank body of curved cross section with inner and outer channels, bending the ends of the inner channels outward at an inclination, and closing over the ends of the outer channels 25 by bending and welding along surfaces inclining inwardly so that both the inner and outer channels freely pass the fluid currents 30 at their ends.

7. The method of forming a tank of sheet metal comprising the steps of corrugating and bending the sheet metal to form a tank body of curved cross section with inner and outer channels, bending the ends of the inner channels outward at an inclination, closing over the ends of the outer channels 35 along surfaces inclining inwardly by bringing the edges together and welding so that 40 both the inner and outer channels freely

pass the fluid currents at their ends and welding circular members to the outwardly inclining ends of said inner channels at each end of the tank.

8. A method of forming a tank body of 45 sheet metal comprising the steps of corrugating said sheet metal with successive rounded bends in the sheet metal and relatively flat portions intervening between said bends to provide outer and inner channels, bending said corrugated sheet metal into the curved form of the tank body by spreading the outer bends to space them farther apart and correspondingly widening the outer channels, and closing over the ends 50 of the inner channels of said corrugations by bending and welding along surfaces inclining inwardly so that both the inner and outer channels freely pass the fluid currents 55 at their ends.

9. A method of forming a tank body of sheet metal comprising the steps of corrugating said sheet metal with successive rounded bends in the sheet metal and relatively flat portions intervening between said 60 bends to provide outer and inner channels, bending said corrugated sheet metal into the curved form of the tank body by spreading the outer bends to space them farther apart 65 and correspondingly widening the outer channels, and closing over the ends of the inner channels of said corrugations by bending and welding along surfaces inclining 70 inwardly so that both the inner and outer channels freely pass the fluid currents at 75 their ends, the opposite flat sides of each inner channel being nearly parallel to each other.

ROBERT V. BINGAY.
